UNITED STATES PATENT OFFICE.

WILLIAM H. BRIGMAN, OF ORANGEBURG, SOUTH CAROLINA.

WEIGHT-CHANGING DEVICE FOR TOP-ROLL-SADDLE MECHANISM.

Application filed August 7, 1925. Serial No. 48,842.

This invention relates to improvements in weight changing devices for top roll saddle mechanisms of spinning frames, and has for its general object the provision of a novel 5 device including a stirrup cooperating with the saddle of the top roll and engaged by a lever carrying an adjustably mounted weight.

An important object of the invention is 10 to provide a mechanism of this character which will dissipate, to a great extent, the stresses resulting from the vibration of the spinning frame without transmitting such stresses to the saddle and thence to the rolls.

Another object of the invention is to provide a device of this character embodying means for distributing the load resulting 15 from the provision of a lever carrying a weight so that the load on the middle and back rolls will be relatively slight so that 20 the work of the machine will be improved.

Another object is to provide a device of 25 this character embodying a novel lever and stirrup arrangement together with a fulcrum for the lever.

An additional object is to provide a device of this type which will be simple and inexpensive in manufacture, easy to install, positive in action, efficient and durable in 30 service, and a general improvement in the art.

With the above and other objects and advantages in view, the invention consists 35 in the details of construction and the arrangement and combination of parts to be hereinafter more fully described and claimed, and illustrated in the accompanying drawings, in which:—

Figure 1 is a side elevation of a portion 40 of a spinning frame or machine showing the invention applied thereto.

Figure 2 is an end elevation of the invention, a portion of the frame being illustrated by dot and dash lines.

Figure 3 is a detail elevation of the stirrup, and

Figures 4 and 5, are detail views.

Referring more particularly to the drawings, the numeral 1 designates the top roll, 50 2 represents the saddle for the top roll and 3 is the stirrup which connects the saddle with the lever 4. The lever 4 is shown as consisting of an elongated flat bar having one end provided with a plurality of notches 55 5 within a selected one of which may be engaged a suspension member 6 carrying a

weight 7. At its other end, the lever is twisted or otherwise formed to provide a widened portion 8 which is of hook shape and adapted to be engaged within an eye 60 bolt 9 anchored into the frame 10 of the machine and serving as a fulcrum for the lever.

The stirrup 3 is likewise in the form of a flat elongated bar and has one end provided 65 with an opening 11 and a slot or notch 12 leading thereto for the reception of the widened end portion of the lever 4, the shape of the openings being such that the necessary play is present to permit the lever to 70 accommodate itself to the proper positions. At its other end, the stirrup is formed with an opening 13 and a notch or slot 14 leading thereto for the purpose of engaging 75 with the saddle 2 of the spinning frame or machine. Obviously, the lever may be readily disengaged from the eye bolt 9 which constitutes the fulcrum member, whenever such is desired.

From the foregoing description and a 80 study of the drawings, it is believed that the construction, operation and advantages will be readily apparent to one skilled in the art without further explanation. Attention is, however, invited to the fact that 85 the large wearing surfaces provided are of great advantage inasmuch as the weight will be distributed, a feature which is essential in spinning good yarn. The provision of the opening in the lower end of the stirrup 90 enables the operator of the spinning frame to place the lever in working position from the back or inside of the machine which is much quicker and better than the present way of placing the levers in place or position. 95

While I have shown and described the preferred embodiment of the invention, it should be understood that I reserve the right to make such changes in the form, construction and arrangement of parts as will not depart from the spirit of the invention or the scope of the subjoined claim. 100

Having thus described the invention, I 105 claim:—

In a spinning machine, the combination with the frame, top roll and top roll saddle, of an eye bolt mounted upon the frame and projecting upwardly, an elongated lever carrying an adjustably mounted weight at one 110 end and having its other end formed with a laterally widened portion, concaved at

its upper side to define a hook pivotally engaged within said eye bolt, and a stirrup having one end formed with a rectangular opening and notches at the upper and lower edges thereof, said opening and notches being for engagement with the top roll saddle, and the other end of the stirrup having a wide opening therein and a relatively narrow slot at the lower end thereof communicating therewith, said wide opening in

the second mentioned end being for the accommodation of the laterally widened end portion of the lever and the relatively narrow slot being for the accommodation of the lever at its juncture with the widened portion. 15

In testimony whereof I affix my signature.

WILLIAM H. BRIGMAN.
